US00D571497S

(12) **United States Design Patent**
Chan et al.

(10) **Patent No.:** **US D571,497 S**
(45) **Date of Patent:** **** Jun. 17, 2008**

(54) **LIGHTING DEVICE**

(75) Inventors: **Wai Kwan Chan**, Tai Po (HK); **Paul Kenneth Pickard**, Morrisville, NC (US); **Gerald H. Negley**, Durham, NC (US); **Antony Paul Van De Ven**, Sai Kung (HK); **Gary David Trott**, Morrisville, NC (US); **Edward Roger Adams**, Englewood, TN (US)

(73) Assignee: **Cree LED Lighting Solutions, Inc.**, Durham, NC (US)

(**) Term: **14 Years**

(21) Appl. No.: **29/279,354**

(22) Filed: **Apr. 27, 2007**

(51) LOC (8) Cl. **26-05**

(52) U.S. Cl. **D26/74**

(57) **CLAIM**

The ornamental design for a lighting device, as shown and described.

DESCRIPTION

FIG. 1 is a front view of the lighting device in accordance with our new design, the lighting device being in an expanded configuration;

FIG. 2 is a back view of the lighting device depicted in FIG. 1 in its expanded configuration;

FIG. 3 is a right side view of the lighting device depicted in FIG. 1 in its expanded configuration;

FIG. 4 is a left side view of the lighting device depicted in FIG. 1 in its expanded configuration;

FIG. 5 is a top view of the lighting device depicted in FIG. 1 in its expanded configuration;

FIG. 6 is a bottom view of the lighting device depicted in FIG. 1 in its expanded configuration;

FIG. 7 is a top, right, back, perspective view thereof;

FIG. 8 is a bottom, right, front, perspective view thereof.

FIG. 9 is a right side view of the lighting device in a collapsed configuration;

FIG. 10 is a back view of the lighting device in its collapsed configuration;

FIG. 11 is a front view of the lighting device in its collapsed configuration;

FIG. 12 is a left side view of the lighting device in its collapsed configuration;

FIG. 13 is a top view of the lighting device in its collapsed configuration;

FIG. 14 is a bottom view of the lighting device in its collapsed configuration;

FIG. 15 is a top, right, back perspective view of a lighting device in its collapsed configuration; and,

FIG. 16 is a bottom, right, front, perspective view of the lighting device in its collapsed configuration.

The broken lines in the drawings represent unclaimed environmental subject matter.

1 Claim, 16 Drawing Sheets
